UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING MACHINE.

Application filed March 31, 1922. Serial No. 548,294.

To all whom it may concern:

Be it known that I, JOHN A. WHERRY, a citizen of the United States, residing in New Orleans, in the parish of Orleans, and State of Louisiana, have invented certain new and useful Improvements in Typewriting Machines, of which the following is a specification.

This invention relates to typewriting machines, and particularly to means for enabling a condensed record-sheet or proof-sheet to be inserted in the machine and detained therein in adjusted position while other work-sheets, such as bills, statements, or ledger-sheets, may be inserted, positioned, typed upon and removed from the machine in succession one after the other, so that the items typed upon each of the several latter sheets will all appear seriatim upon the condensed record-sheet.

The object of the invention is to produce a device, of the kind above noted, of simple and inexpensive construction, and which may be embodied in a usual or standard form of typewriting machine without the necessity of making any changes therein other than to install thereon the additional parts required by the present improvement.

The invention comprises a bail pivoted upon the platen-frame and carrying adjacent its ends paper-guiding and holding devices, such as paper-fingers, to co-operate with the front and upper part of the platen for guiding an inner work-sheet, such as a condensed record-sheet, upwardly and rearwardly below and behind the front bar or front rod of the bail, upon which is mounted a gage for an outer work-sheet, such as a bill, a statement, or a ledger-sheet. The usual releasable feed-rolls running upon the bottom of the platen are cast off, and the bail, together with the parts carried thereby, is swingable away from the platen to enable the inner sheet or condensed record-sheet to be adjusted prior to the insertion of the first outer sheet. Said gage, which may be a side-edge gage, is pivoted on said front rod of the bail to swing away from the platen, so as not to obstruct the insertion of the inner sheet or condensed record-sheet, and to swing into proximity to the platen, so that the outer sheet, when inserted, may be directed upwardly at the front of said gage and the front rod of the bail, said outer sheet being thus inserted and adjusted while

the said feed-rolls are released. The invention further comprises, in combination with said bail and said parts carried thereby, an upper rear paper-table located in spaced relation above the usual rear paper-table, for directing the inner sheet or condensed record-sheet to the introductory side of the platen, so as to hold this inner sheet out of the way of the insertion of the successive outer sheets, feed-rolls being provided to run upon the rear of the platen adjacent the lower part of the rear paper-table for feeding the condensed record-sheet downward to the said usual lower feed-rolls and to the usual paper-apron beneath the platen, said rear feed-rolls being also effective to co-operate with said paper-holding devices or paper-fingers at the delivery side of the platen to detain the condensed record-sheet in adjusted position in the machine during the insertion and positioning of the successive outer work-sheets.

Other features and advantages will hereinafter appear.

In the accompanying drawings,

Figure 1 is a front elevation of the platen-frame and parts carried thereby of an Underwood Standard typewriting machine, having the present invention embodied therein and showing the parts thereof in their effective positions.

Figure 2 is a substantially central front-to-rear vertical section of what is shown in Figure 1, and further shows, in broken lines, the side-edge gage for the outer work-sheet as tilted rearwardly on the bail-rod to a position providing for the insertion of the inner or condensed record-sheet.

Figure 3 is a similar view, with the bail and parts carried thereby swung upward and rearward away from the platen to provide for adjusting the condensed record-sheet.

In carrying out the present invention, a wide inner sheet 1, which is a condensed record-sheet or proof-sheet, is inserted at the introductory side of the revolute platen 2 over an upper rear paper-table 3 having an upper straight part and a lower part curved around the upper part of the platen at the rear thereof. The upper rear paper-table 3 is rigidly supported upon the usual platen-frame by the end walls 4, in which the platen-axle 5 is journaled, by means of lugs or sleeves 6 on the rear paper-table 3, which are rigidly fixed, by means of set

screws 7, upon the usual rear transverse tie-rod 8 which extends between and is rigidly fixed in the upper part of the end walls 4 rearwardly from the top of the platen and above the rear part of the platen. The platen 2 is now rotated, either by the usual line-space mechanism including the line-space ratchet wheel 9, or preferably and more rapidly by means of the usual handle-knob 10, to feed the condensed record-sheet 1 downwardly at the introductory side of the platen, such feeding of this record-sheet 1 being accomplished by means of upper rear auxiliary or supplemental spring-pressed feed-rolls 11, which are mounted upon the paper-table 3 by means of spring arms 12 which press these rolls towards the platen through openings 13 provided in the lower curved part of the paper-table 3.

As the platen is rotated, the condensed record-sheet 1 is fed downward until its leading edge passes upon the usual curved paper-apron 14 beneath the platen and between the platen and the usual normally effective releasable front and rear feed-rolls 15 which run upon the lower side of the platen. By continuing the rotation of the platen, the leading edge of the condensed record-sheet 1 will pass upward at the front or delivery side of the platen beneath curved paper-fingers 16, adjacent the ends of the platen, and beneath spring-pressed paper-holding rollers 17 adjacent the upper parts of the paper-fingers, said paper-fingers 16 and rollers 17 forming paper-guiding and paper-holding devices for the condensed record-sheet 1. The advancing condensed record-sheet 1 is guided by the paper-fingers 16 around the platen rearwardly beneath and to the rear of a rod or bar 18 extending along the top of the platen and which forms the front bar of a swingable bail having end arms 19 pivoted upon the rear tie-rod 8 just within the frame ends 4 of the platen-frame. The end arms 19, in which the front bail-rod 18 is rigidly supported, have front end parts 20 turned over inwardly at the front of the bail-rod 18, the upper ends of the paper-fingers 16, as well as spring mountings for the rollers 17, being secured to these turned-over ends 20 by means of screws 21.

In order to position or adjust the condensed record-sheet to the desired writing position, the lower feed-rolls 15 are now released by means of a suitable cast-off device, not shown, and the bail, comprising the side arms 19 and front bar 18, is swung upwardly and rearwardly from the effective position, shown in Figures 1 and 2, to the ineffective position shown in Figure 3, thereby leaving the condensed record-sheet 1 free to be easily straightened and adjusted, the light pressure thereon of the rear upper feed-rolls 11 not interfering with such adjustment. The swinging bail may be held at its forward position, in which the paper-fingers 16 and rollers 17 are effective, by means of a curved leaf spring 22 carried within a U-shaped rear end part 23 of one of the bail arms 19, for pressing a short rod or roller 24 into a groove formed along the lower side of the tie-rod 8, as shown at the left in Figure 1. A similar holding device, not shown, is also preferably provided at the other side of the machine. These devices will also be effective to hold the bail at the ineffective position shown in Figure 3.

After the condensed record-sheet 1 has been adjusted, the bail is swung forward from the Figure 3 to the Figures 1 and 2 position, thereby rendering the paper-fingers 16 and rollers 17 carried by the bail effective to co-operate with the rear upper feed-rolls 11 for detaining the sheet 1 in the machine and holding it in its adjusted position. While the condensed record-sheet 1 is thus detained and held and with the lower feed-rolls 15 released, an outer narrower work-sheet 25, which may be a bill or a statement or a ledger-sheet, is inserted at the introductory side of the platen over a lower usual rear paper-table 26, which may form part of the platen-frame, and which, in the machine illustrated in the drawings, is shown as continuous or formed in one piece with the paper-apron 14. The outer narrower work-sheet 25 is pushed around from the rear over the paper-apron 14 beneath or at the outside of the condensed record-sheet 1 and above the released lower feed-rolls 15 until its leading edge rises above the printing point on the platen, indicated in Figure 2 by the type-head 27 carried by the swinging type-bar 28, and is adjusted or straightened by means of the usual wing-scales, not shown. As the outer sheet 25 is further advanced, its leading edge will pass to the front of the floor portion 29 of a gage-member or side-edge gage having an outstanding side flange 30 against which the outer work-sheet 25 may be gaged laterally at its adjacent side edge. This side-edge gage is carried by the front bar 18 of the swinging bail, and in the normal or effective position of the gage the lower edge of its floor portion 29 rests in proximity to the front of the platen just above the printing line, as shown in Figures 1 and 2, so as to be effective to receive and guide the advancing outer work-sheet 25.

To provide for the insertion of the inner condensed record-sheet 1, as hereinbefore described, the side-edge gage may be swung from its normally effective position, shown in Figure 1 and also shown in full lines in Figure 2, to an upper position thereof, shown in broken lines in Figure 2, so as not to obstruct the leading edge of the ad-

vancing condensed record-sheet 1. Also during the adjustment of the condensed record-sheet 1, hereinbefore described, the side-edge gage for the outer sheet 25 swings 5 with the bail-rod 18 upwardly and rearwardly to the position shown in Figure 3, so as to be entirely out of the way. In order to provide for swinging the side-edge gage between the two positions thereof, shown in Figure 2, it is pivoted on the bail-rod 18 by means of a U-shaped portion, comprising ears 31 and an upper connecting member 32, which is joined by means of an intermediate connecting portion 33 to the 10 upper end of the floor portion 29 of the gage. The entire gage-member may be formed from a single piece of sheet-metal, as shown in Figures 2 and 3. The gage-member or side-edge gage may be slid along 15 the bail-rod 18 between the paper-fingers 16 for adjusting it to different gaging positions. For frictionally holding the gage at its different positions of adjustment and also for holding it at its effective position, 20 shown in Figures 1 and 2, as well as for frictionally detaining it at the ineffective position shown in broken lines in Figure 2, a bowed leaf spring 34, interposed between the ear-connecting member 32 and the bail-rod 18, presses a small detent roller or rod 35 against the bar 18, and in the effective or gaging position of the gage presses this roller or rod 35 into a groove extending 25 along the top of the bail-rod 18 throughout its length, as shown in Figure 2, for thereby more securely holding the gage at the gaging position. Of course, a carbon-paper-sheet will be interposed between the work-sheets 1 and 25 and may be conveniently inserted along with the condensed record-sheet 30 1, and the forward end of the carbon-sheet may be folded over the leading edge of the condensed record-sheet 1 in order to facilitate the insertion of these sheets.

45 During the insertion and adjustment of the outer work-sheet 25, as above noted, the inner condensed record-sheet 1 and its accompanying carbon-sheet are securely held in position in the machine by means of the upper rear feed-rolls 11 and the front paper-holding devices comprising the paper-fingers 16 and rollers 17. When the outer work-sheet 25 has been adjusted, as above noted, the lower feed-rolls 15 are thrown on or 40 made effective and the typing may proceed, all the sheets being advanced or line-spaced by means of the usual line-space mechanism. Should the outer work-sheet 25 show any 45 tendency to curl or fall over forwardly away from the floor 29 of the side-edge gage, such tendency may be prevented by bringing into use the usual paper-guiding finger provided upon the Underwood machine to engage the paper adjacent to the printing point, or, if desired, the gage may be swung upward on 50

the bail-rod 18 to the broken-line position thereof, shown in Figure 2, and the upper end of the outer sheet 25 may then be passed upward to the rear of the bail-rod 18, but preferably is kept at the front. 55

Obviously, in the carrying out of the invention, as illustrated in the drawings, the outer work-sheet 25 will be an original or ribbon copy while the condensed record-sheet 1 will be a carbon copy forming a record of all the items typed upon the successively inserted outer sheets. After the item or items which are to appear up on the outer work-sheet 25 have been typed thereon, the lower feed-rolls 15 are cast off or released 60 and the typed outer sheet 25 is then withdrawn from the front of the machine, while the inner condensed record-sheet 1, containing a carbon record of what has been typed upon the outer sheet 25, is detained in the 65 machine and held therein in adjusted position by means of the upper auxiliary or supplemental feed-rolls 11 and by the paper-holding devices at the delivery side of the platen comprising the paper-fingers 16 and 70 pressure rollers 17. While the inner condensed record-sheet is thus securely detained in position in the machine, another outer sheet is inserted and positioned in the manner above described for the first outer sheet 75 25, and this last-inserted sheet is then typed upon and removed similarly to the first outer sheet 25, and so on successively for any number of outer sheets of which it is desired to make a carbon record upon the condensed 80 record-sheet 1. It is understood, of course, that after any outer sheet has been gaged and the lower feed-rolls 15 made effective, 85 all of the sheets may be line-fed forward to any extent desired or required by operating the usual line-space mechanism. Also, in 90 case additional space is desired between the successive entries on the condensed record-sheet 1, this sheet may, in the usual way, be independently line-spaced to the desired extent between the times of the insertion of the 95 successive outer sheets.

Variations may be resorted to within the scope of the invention, and portions of the improvements may be used without others. 100

Having thus described my invention, I 105 claim:

1. In a front-strike typewriting machine, the combination with a platen-frame and a revoluble platen having an axle journaled in 110 the platen-frame, of an upper rear paper-table carried by the platen-frame for directing an inner work-sheet to the introductory side of the platen, a lower rear paper-table on the platen-frame for directing an outer work-sheet to the introductory side of the platen, a paper-apron below the platen for 115 guiding both of said work-sheets around the platen, a bail pivoted on the platen-frame above and to the rear of the platen-axle and 120

125

130

having a front bar to extend along the platen at the delivery side thereof and swingable upwardly and rearwardly away from the platen, paper-holding devices carried by the 5 bail for pressing the inner work-sheet towards the platen to hold it in position while the outer work-sheet is inserted and adjusted thereover, and a gage for the outer work-sheet mounted upon the front bar of 10 the bail.

2. In a front-strike typewriting machine, the combination with a platen-frame and a revoluble platen having an axle journaled in the platen-frame, of an upper rear paper-table carried by the platen-frame for directing an inner work-sheet to the introductory side of the platen, a lower rear paper-table on the platen-frame for directing an outer work-sheet to the introductory side of the 15 platen, a paper-apron below the platen for guiding both of said work-sheets around the platen, a bail pivoted on the platen-frame above and to the rear of the platen-axle and having a front bar to extend along the platen 20 at the delivery side thereof and swingable upwardly and rearwardly away from the platen, paper-holding devices carried by the bail adjacent the ends thereof for pressing the side margins of the wider inner work-sheet towards the platen to hold it in position while the narrower outer work-sheet is 25 inserted and adjusted thereover, and a side-edge gage for the narrower outer work-sheet mounted on and slidale along the 30 front bar of the bail between said paper-holding devices.

3. In a front-strike typewriting machine, the combination with a platen-frame and a revoluble platen journaled therein, of a 40 paper-apron beneath the platen for guiding work-sheets around the platen, releasable feed-rolls to run on the lower side of the platen, a lower rear paper-table for directing an outer work-sheet to the paper-apron to be 45 engaged by said feed-rolls, an upper rear paper-table for directing an inner work-sheet to said paper-apron to be engaged by said feed-rolls, means adjacent the upper rear paper-table to co-operate with the 50 platen to hold the inner work-sheet in position while the outer work-sheet is inserted and adjusted thereover when said feed-rolls are released, a bail pivoted on the upper part of the platen-frame and including a front 55 bar to extend along the platen at the delivery side thereof to be swingable upwardly and rearwardly away from the platen and forwardly and downwardly towards the platen and beneath which said inner work-sheet may pass, and a gage carried by the 60 front bar of the bail to swing therewith to be utilized in adjusting the outer work-sheet over the inner work-sheet.

4. In a front-strike typewriting machine, 65 the combination with a platen-frame and a

revoluble platen journaled therein, releasable feed-rolls to run on the lower side of the platen, a paper-apron for guiding work-sheets between the platen and feed-rolls, a lower rear paper-table for directing an outer work-sheet to the paper-apron, an upper rear paper-table for directing an inner work-sheet to the paper-apron, a feed-roll to run upon the rear of the platen adjacent the lower part of the upper rear paper-table for feeding the inner work-sheet downward to the paper-apron and said lower feed-rolls, and for holding the inner sheet in adjusted position on the platen to enable the outer sheet to be inserted and 70 adjusted when said lower feed-rolls are released, a bail pivoted to the upper part of the platen-frame and having a front bar extending along the platen at the delivery side thereof above the writing line, said bail being swingable to move said bar away from or towards the platen, and a gage carried by the front bar of the bail for use in adjusting the outer work-sheet over the inner work-sheet while said lower feed-rolls are 75 released and the inner work-sheet is held by said rear feed-roll.

5. In a front-strike typewriting machine, the combination with a platen-frame and a revoluble platen journaled therein, of means for directing work-sheets to the introductory side of the platen, a paper-apron for guiding the work-sheets beneath the platen, releasable feed-rolls to run upon the lower side of the platen, a bail pivoted upon the 80 upper part of the platen-frame and including a front bar swingable toward and away from the platen at the delivery side thereof, paper-fingers carried by the bail adjacent its ends for guiding the leading edge of an inner wider work-sheet rearwardly beneath said bar and for holding said work-sheet against the platen while an outer narrower work-sheet is inserted and adjusted between said paper-fingers over the inner work-sheet, and a side-edge gage for the outer work-sheet slidale along said bar to different positions of lateral adjustment between 85 said paper-fingers, said side-edge gage comprising a floor portion at the front of which 90 said outer work-sheet may pass and an outstanding flange portion against which the side edge of said outer work-sheet may be gaged, said side-edge gage being pivoted to swing upon said bar so that the lower edge 95 of said floor portion may be swung upwardly away from the platen to enable said inner sheet to pass upward behind said gage and said bar, or may be swung downward into close proximity to the platen to guide 100 said outer sheet upwardly on said floor portion at the front of said bar.

6. In a front-strike typewriting machine, the combination with a platen-frame and a 105 revoluble platen journaled therein, of a 110

- paper-apron for guiding work-sheets beneath the platen, releasable feed-rolls to run upon the lower side of the platen, a bail pivoted upon the upper part of the platen-
 5 frame and including a front bar swingable toward and away from the platen at the delivery side thereof, paper-fingers carried by the bail adjacent its ends for guiding the leading edge of an inner wider work-sheet
 10 rearwardly beneath said bar and for holding said work sheet against the platen while an outer narrower work-sheet is adjusted between said paper-fingers over the inner work-sheet, a side-edge gage for the outer
 15 work-sheet slidable along said bar to different positions of lateral adjustment between said paper-fingers, a lower rear paper-table for directing the outer work-sheet to the paper-apron, an upper rear
 20 paper-table for directing the inner work-sheet to the paper-apron, and a spring-pressed feed-roll to run upon the rear of the platen adjacent the lower part of the upper rear paper-table to co-operate with the platen for feeding the inner sheet downward to the paper-apron and said lower feed-rolls, and also
 25 to co-operate with said paper-fingers for holding the inner sheet in adjusted position while the outer sheet is inserted and adjusted over the inner sheet by means of said gage while said lower feed-rolls are released.
 30 8. In a typewriting machine for typing entries upon a succession of short outside work-sheets and at the same time typing all of said entries upon a relatively long record-sheet common to all of said outside sheets, a rotary platen, feed-rolls co-operating with the platen to advance a short sheet and the record-sheet together, and collating rolls at both the introductory and delivery sides of the platen to clamp the record-sheet stationary against the platen during insertion, adjustment and removal of the outside sheets.
 35 9. In a typewriting machine for typing entries upon a succession of short outside work-sheets and at the same time typing all of said entries upon a relatively long record-sheet common to all of said outside sheets, a rotary platen, a paper-table at the introductory side of the platen for guiding the outside sheets to the platen, a rearwardly inclined auxiliary rear paper-table spaced to the front from the first table and secant to the platen at the upper rear portion thereof to provide a wide unobstructed throat in conjunction with the first paper-table for the introduction of the outside sheets, auxiliary rolls behind the auxiliary paper-table for advancing the record-sheet into the machine and for clamping the record-sheet stationary against the platen during insertion, adjustment and removal of the outside sheets, and an extension on the auxiliary table conforming substantially to the platen and extending rearwardly and downwardly beyond said auxiliary rolls to hold the rear end of the record-sheet out of the way of the outside sheets, after it has passed beyond the auxiliary rolls, to assure the insertion of the outside sheets to the outside of the record-sheet.
 40 10. In a typewriting machine for typing entries upon a succession of short outside work-sheets and at the same time typing all of said entries upon a relatively long record-sheet common to all of said outside sheets, a rotary platen, a paper-table at the introductory side of the platen for
 45 that the lower edge of said floor portion may be swung upwardly away from the platen to enable said inner sheet to pass upward behind said gage and said bar, or may be swung downwardly into close proximity to the platen to guide said outer sheet upwardly on said floor portion at

guiding the outside sheets to the platen, a rearwardly inclined auxiliary rear paper-table spaced to the front from the first table and secant to the platen at the upper 5 rear portion thereof to provide a wide unobstructed throat in conjunction with the first paper-table for the introduction of the outside sheets, auxiliary rolls behind the auxiliary paper-table for advancing the 10 record-sheet into the machine and for clamping the record-sheet stationary against the platen during insertion, adjustment and removal of the outside sheets, and an apron conforming substantially to 15 the platen and extending rearwardly and downwardly beyond said auxiliary rolls to hold the rear end of the record-sheet out of the way of the outside sheets, after it has passed beyond the auxiliary rolls, to assure 20 the insertion of the outside sheets to the outside of the record-sheet.

11. In a typewriting machine for typing entries upon a succession of short outside work-sheets and at the same time typing 25 all of said entries upon a relatively long record-sheet common to all of said outside sheets, a rotary platen, feed-rolls beneath the platen and co-operating therewith to advance the outside sheets together

with the record-sheet, auxiliary rolls at the 30 delivery side of the platen to run upon the side margins of the record-sheet to clamp it stationary during insertion, adjustment and removal of the outside sheets, a side gage 35 for the outside sheets within the bounds of the record-sheet, and a common support for the auxiliary rolls and the side gage mounted to move the rolls and the gage upwardly and rearwardly to give access to the record-sheet while keeping the record 40 and outside sheets in the machine, so that both sheets may be erased and corrected at the same time.

12. In a typewriting machine for typing entries upon a succession of short outside work-sheets and at the same time typing all of said entries upon a relatively long record-sheet common to all of said outside sheets, a rotary platen, a side-edge gage 45 for the outside sheets within the bounds 50 of the record-sheet at the delivery side of the platen, and means for lifting the side-edge gage away from the record-sheet.
